UNITED STATES PATENT OFFICE.

JOSEPH E. KENNEDY, OF NEW YORK, N. Y.

PULVERIZING APPARATUS.

1,356,292.

Specification of Letters Patent. Patented Oct. 19, 1920.

Application filed February 2, 1918. Serial No. 215,052.

To all whom it may concern:

Be it known that I, JOSEPH E. KENNEDY, a citizen of the United States, and a resident of the borough of Manhattan, city, county, and State of New York, have invented certain new and useful Improvements in Pulverizing Apparatus, of which the following is a specification.

My improvements relate to the class of 10 grinding machinery in which rock, ore, coal, or analogous crude material is comminuted by means of crushing rollers traveling over and inside an attrition ring or die, between which and said rollers the raw material is 15 fed, to be removed by air blast as fast as reduced to the proper degree of fineness. The invention consists in the specific construction, combination and arrangement of parts herein described and claimed, distinctive features being the central induction of the air 20 vehicle, the means for suspending and rotating the crushing rollers, the method of lubrication, the means of feeding the raw material to and between the crushing rollers and 25 the attrition ring, and other details, all as hereinafter fully set forth.

In the accompanying drawings,

Figure 1, is a diagrammatic view illustrating an installation in which my improved pulverizer forms a component part;

Fig. 2, is an elevation of what may be designated as the feed side of my improved pulverizer;

Fig. 3, is a central vertical sectional elevation taken upon plane of line 3—3, Fig. 2;

Fig. 4, is a central vertical sectional elevation taken upon plane of line 4—4, Fig. 3;

Fig. 5, is a horizontal sectional elevation taken upon plane of line 5—5, Fig. 3;

Fig. 6, is a horizontal section taken upon plane of line 6—6, Fig. 3;

Fig. 7, is a top view of a portion of the drive head showing one of the mounts for one of the crushing roller spindles;

Fig. 8, is a sectional elevation taken upon plane of line 8—8, Fig. 7;

Fig. 9, is a top view of a portion of the drive head showing one of the mounts for one of the plow spindles;

Fig. 10, is a sectional elevation taken upon plane of line 10—10, Fig. 9.

Fig. 1, represents diagrammatically the general relationship of my improved roll pulverizing apparatus in and to a system

55 for the reduction of raw material and the

collection of the product, by reference to which it will be seen that my pulverizer P, is interposed in a forced air circulation generated by the exhaust E, which forces the air carrying the comminuted material from 60 the pulverizer P, through the conduit e, to the collectors C, C', from which the product is deposited by gravity into the bin B, the clarified air being returned through the conduit e, to the lower portion of the pul- 65 verizer P, to be again used as a vehicle for the removal of the impalpable powder from the crushing chamber as hereinafter set forth.

The raw material is fed from the primary 70 bin A, through a spout a, to the feed hopper f, from which it is transferred by positive means (as by the reciprocating forwarder f') through the passage f², to the floor r, of the reduction chamber R, as will be understood by reference more particularly to Fig. 3, of the drawings. The reduction chamber R, is essentially cylindrical in configuration, being formed within the trunk section p, of the pulverizer casing, said trunk 80 section p, being supported upon foundation piers p'. Said trunk section p, is formed with a hollow central bearing post p², upon and in which the drive head D, and its drive shaft d, are mounted, the central bearing 85 post p², being essentially a sleeve extending down to the bottom plate of the trunk section p, the lower part of which contains the air inlet compartment I, situated immediately below the floor r, of the reduction 90 chamber R, and communicating with the latter through a central delivery aperture i. The lower extremity of the return air conduit e, from the collectors C, C', connects directly with the mouth i', of the air inlet compartment I.

p³, is an annular extension of the casing fitting upon the top of the trunk section p, and forming the base support for the shell p⁴, which surmounts the reduction compartment R, and incloses the drive head D, and connections,—the shell p⁴, being provided with a hood p⁵, formed with an exit conduit p⁶, having a downward extension p⁷, into the shell p⁴. Manholes in the shell p⁴, and 100 hood p⁵, provided with suitable closures, afford access when necessary to the inclosed space and to the reduction chamber R.

The exit conduit p⁶, connects directly with the air exhaust device E, which latter may 110

be of any desired or well known type or construction, that indicated in the drawings being a rotary fan exhaust driven by a belt e' , in engagement with a pulley m , on the 5 main power shaft M, Fig. 1.

The lower extremity of the drive shaft d , rests upon an adjustable seat d' , mounted on a cap bracket d'' , secured to the lower part of the gear casing p^8 , which is secured 10 in turn to the lower side of the trunk section p , as shown in Figs. 3 and 4. The gear casing p^8 , is formed with a pocket p^9 , for the accommodation of the lowest portion of the miter pinion m' , on the counter shaft M', 15 which pinion meshes with the gear d^4 , secured to the drive shaft d , said pocket also performing the function of a well for the lubricating oil.

The inner journal of the counter shaft M', 20 is seated in a bearing p^{10} , formed for it in the gear casing p^9 , while its outer journal is supported in a bearing t , on the pillow block T. Secured to the countershaft is a large driven pulley m^2 , connected by a belt 25 m^3 , (Fig. 1) with a still larger drive pulley m^4 , on the main power shaft M. The latter also has the drive pulley m , connected by belt e' , with the driven pulley e^2 , on the exhaust E. A small drive pulley m^5 , on 30 the countershaft M', actuates a belt f^3 , which transmits motion to the driven pulley f^4 , on the shaft f^5 , by means of which the feed mechanism is operated. Another small drive pulley m^6 , on the countershaft M', by 35 means of the belt m^7 , and driven pulley 1, operates the pump L, by which a forced circulation of the lubricant is maintained as and for the purpose hereinafter set forth.

N, is an attrition ring seated in the 40 upper part of the trunk section p , of the casing, its exterior periphery being beveled slightly to fit a correspondingly inclined concavity p' , in said trunk section p , as shown in Figs. 3 and 4. The attrition ring 45 N, is held to its seat by wedge blocks n , positioned in recesses formed for them in the annular base extension p^8 , on top of the trunk section p . The function of the attrition ring N, is to act as an anvil, die, or 50 tread way for the crushing rollers K, which are pivotally suspended upon the drive head D, which is rigidly mounted as before intimated on the upper extremity of the drive shaft d .

55 The construction and mounting of the crushing rollers K, will be understood more particularly by reference to Figs. 7 and 8. Thus the tire of each roller K, is secured to a hub section k , forming the lower part of a 60 rotatable sleeve K', which is mounted on the non-rotatable spindle J, rigidly secured to the rocker bearing J'. The latter is fulcrumed on the trunnion shaft j , supported in bearings d^4 , d'' , on the drive head D, 65 which latter is recessed, as at d^5 , between

said bearings d^4 , d'' , to allow the rocker bearing J, to conform to the inclination imparted thereto by the roller K, when deflected by the material under treatment. Stops d^6 , d'' , on the drive head D, limit the outward thrust of the rollers K. Key pins j' , j'' , lock the spindle J, to the rocker bearing J', preventing its turning therein, as will be seen by reference to Fig. 7.

An annular shoulder j^2 , on the non-rotatable spindle J, supports the rotatable sleeve K', and roller K, the sleeve K', being formed for the purpose with a recess k^2 , and provided with the cap piece k^3 , which affords the upper bearing for said annular shoulder j^2 , on the spindle J, as will be seen by reference to Fig. 8. j^3 , j^4 , are wear and spacing washers or plates, interposed between said annular shoulder j^2 , and the opposed bearing surfaces on the sleeve K'. I prefer to 85 secure the tire of the roller K, to the hub section k , of the rotatable sleeve K', by making said hub section k , conoidal and threading it peripherally, the tire section of the roller K, being correspondingly formed and 90 threaded to receive the hub section k . The pitch of the thread k , is reversed to the direction of rotation of the roller K, so that the working strain on the latter tends to preserve and tighten the connection between the 95 parts.

The non-rotatable spindle J, is formed with a central duct j^4 , with which the lubricant cup j^5 , communicates. Said central duct j^4 , extends down to the well k^4 , in the 100 tire section K, below the hub section k , and it also has lateral ducts k^5 , which distribute the lubricant at intermediate points between the rocker bearing J', and said space k^4 , in the roller K.

Thus constructed and mounted the crushing rollers K, operate with a minimum amount of frictional resistance, and are free to adapt themselves to the irregularities of the raw material fed between them and the 110 attrition ring N.

This feed to the rollers of the material to be reduced is effected by means of the plows S, which take up and agitate the material introduced through the inlet f^2 , to the floor r , of the reduction chamber R. The plows S, serve the material to the crushing rollers K, in advance of, and in the line of rotation of said rollers, elevating the material from the floor r , of the reduction chamber R, to 115 the peripheries of the rollers K, by which it is pressed against the attrition ring N, the material being returned to the rollers until reduced sufficiently to be taken up by the air vehicle as hereinafter set forth. The 120 plows not only thus raise and deliver the material to and between the crushing rollers K, and the attrition ring N, but they also act as agitators to stir up the material and effect a relatively even distribution thereof 130

to the several rollers,—five of which are shown in the drawings as positioned and suspended in equidistant relationship upon the drive head D, although any desired number 5 may be provided, as may be found most expedient.

The plows S, are arranged intermediate between adjacent crushing rollers K, so that a like number are provided, each secured 10 to the lower extremity of its own suspender rod S', the latter being secured to the drive head D, as shown particularly in Figs. 9 and 10. The plow S, is in each case attached to a bracket sleeve s, which fits upon 15 the reduced portion s¹ of the suspender rod S', being clamped by the nut s², against the shoulder s³. By this means the bracket sleeve s, and plow S, may be secured in any prescribed position around the suspender rod S', so as to regulate approximately 20 the scope of action of the plow S, with relation to the attrition ring N, and crushing rollers K.

The upper portion of the suspender rod 25 S', passes through bearings d⁶, d⁷, pendant from the drive head D, and a lock screw d⁸, may be provided by which to secure the suspender rod S', rigidly in its prescribed position. The upper end of the suspender 30 rod S', also has a reduced portion, s⁴, to which is spline-connected the hub h, of an adjusting arm H, by means of which the lateral scope of action of the plow S, may be conveniently varied and regulated with accuracy 35 from above,—said adjusting arm H, being formed for the purpose with a concentric slot h', through which the screw stud d⁹, on the drive head D, protrudes as shown in Fig. 9,—a lock nut d¹⁰, being provided to 40 hold the adjustment, which is further insured by the binding screw d¹¹. Vertical adjustment of the suspender rod S', is provided for by the spline-connection between the hub h, of the adjusting arm H, and the 45 reduced upper portion of the said rod S', as will be understood by reference to Fig. 10, by which it will be seen that the upper extremity of said rod S', is screw threaded, for engagement with the nuts s⁵, s⁶, the 50 lower one of which, s⁵, bears against the hub h, of the adjusting arm H, (said hub resting in turn on the drive head D) while the upper one s⁶, acts as a lock nut. It will thus be seen that ample provision is made for 55 regulating and controlling the position and action of each plow S.

The floor r, of the reduction chamber R, in practice consists of a lining or wear plate as shown in Figs. 3 and 4, by reference to 60 which it will also be seen that the sides of said chamber R, are also protected by a lining r'. In Fig. 4, the space p'', simply represents an ordinary hand hole, having nothing to do with the present invention.

65 As before stated the lower extremity of

the conduit c, communicates directly with the mouth or inlet i', to the air compartment I, beneath the reduction chamber R, delivering the air thereto by pressure derived from the exhaust E, said air blast having 70 been clarified by the precipitation of solid matter therefrom in the "cyclone" collectors C, C'. This clarified air vehicle re-enters the reduction chamber R, through the aperture i, concentric with the hollow central bearing post p², forming part of the trunk section p, of which the casing of air compartment I, also forms a part.

Within the reduction chamber R, the central opening i, is divided by radial partitions i², i², and flanked peripherally by tangential deflectors i³, i³, inclined in the direction of rotation of the drive head D, and against the direction of rotation of the crushing rollers K. These radial partitions 85 i², and tangential deflectors i³, may form a part of the trunk section p, as shown in the drawings, in which case they are provided with a cap plate i⁴, attached to the partitions i², by hook bolts i⁵.

The tangential deflectors i³, cause the air vehicle to impinge against the material stirred up and forwarded by the plows S, and it will be noted that said deflectors are inclined with relation to the plows and to 90 the direction of travel thereof, so that there is no tendency to clog the openings between the deflectors i³, and the jets of air impinge against the material agitated by the plows diagonally across the path of the latter but 100 also in the same general direction so that there can be no back action, pressure or resistance. Thus directed the air vehicle is best adapted to take up and convey away the material comminuted to the degree of lightness 105 prescribed by the strength of the blast or circulatory air system. Hence by varying the force of the air draft and pressure created by the exhaust mechanism the weight of the particles taken from the reduction chamber may be regulated according to requirements.

This centrifugal air blast in the reduction chamber R, is an important factor in my pulverizer, and most effective because it 115 tends constantly to aid in the return of partially reduced material to and in front of the crushing rollers, while sifting out and carrying away the sufficiently comminuted material to be eliminated from the air current in the cyclone collectors.

The pump L, draws the lubricant from the well p⁹, of the gear casing p⁸, through the pipe l', and forces it up through the pipe l'', to the top of the drive shaft d, delivering it to the central duct d'', formed therein, by which it is delivered by the lateral ducts d¹², to the upper bearing d²¹, in the central bearing post p², to return through the latter to the lower bearing p²², 130

- and to the gear chamber p^8 , and well p^9 . By this means the drive shaft d , and gears d' , m' , are positively, practically automatically, and effectually lubricated.
5. What I claim as my invention and desire to secure by Letters Patent is,
1. In pulverizing apparatus of the character designated, in combination, a fixed attrition ring, rotatable crushing rollers opposed to said attrition ring and mounted on traveling spindles, means for feeding material to and between said attrition ring and crushing rollers from below the same, and tangential deflecting means positioned below and centrally as related to said attrition ring for directing air under pressure centrifugally beneath and between said crushing rollers and attrition ring, for the purpose described.
  10. 2. In pulverizing apparatus of the character designated, in combination, a fixed attrition ring, rotatable crushing rollers opposed to said attrition ring and mounted on traveling spindles, means for feeding material to and between said attrition ring and crushing rollers from below the same, and means positioned below and centrally as related to said attrition ring for directing air under pressure centrifugally and tangentially beneath and between said crushing rollers and attrition ring, for the purpose described.
  15. 3. In pulverizing apparatus of the character designated, in combination, a fixed attrition ring, rotatable crushing rollers opposed to said attrition ring and mounted on traveling spindles, means for feeding material to and between said attrition ring and crushing rollers from below the same, and means positioned below and centrally as related to said attrition ring for projecting air under pressure centrifugally and tangentially toward the direction of travel of said crushing rollers but opposed to their direction of rotation, beneath and between said crushing rollers and attrition ring, for the purpose described.
  20. 4. In pulverizing apparatus of the character designated, in combination, a fixed attrition ring, rotatable crushing rollers opposed to said attrition ring and mounted on traveling spindles, means for feeding material to and between said attrition ring and crushing rollers from below the same, plows for agitating said material, and means positioned below, and centrally as related to said attrition ring for projecting air under pressure centrifugally beneath and between said crushing rollers and attrition ring, for the purpose described.
  25. 5. In pulverizing apparatus of the character designated, in combination, a reduction chamber, a fixed attrition ring positioned therein, crushing rollers rotatably mounted to act in conjunction therewith, means for feeding raw material to said reduction chamber, plows for agitating the raw material and feeding same to the crushing rollers, and means positioned centrally with relation to said attrition ring for projecting air under pressure into said reduction chamber centrifugally and tangentially, for the purpose described.
  30. 6. In pulverizing apparatus of the character designated, in combination, a reduction chamber, a fixed attrition ring positioned therein, crushing rollers rotatably mounted to act in conjunction therewith, means for feeding raw material to said reduction chamber, plows for agitating the raw material and feeding same to the crushing rollers, and means positioned centrally with relation to said attrition ring for projecting air under pressure into said reduction chamber centrifugally and tangentially toward the direction of travel of said plows and crushing rollers, but opposed to the direction of rotation of said crushing rollers, for the purpose described.
  35. 7. In pulverizing apparatus of the character designated, in combination, a reduction chamber, means for feeding raw material thereto, a fixed attrition ring positioned in said reduction chamber, a central bearing sleeve extending therethrough, a drive shaft and drive head mounted in and on said central bearing sleeve, means positioned centrally with relation to said attrition ring for projecting air under pressure into said reduction chamber tangentially and centrifugally, and a plurality of crushing rollers pivotally suspended upon said drive head and adapted to act in conjunction with the attrition ring to reduce the raw material.
  40. 8. In pulverizing apparatus of the character designated, in combination, a reduction chamber, means for feeding raw material thereto, a fixed attrition ring positioned in said reduction chamber, a central bearing sleeve extending therethrough, a drive shaft and drive head mounted in and on said central bearing sleeve, means positioned centrally with relation to said attrition ring for projecting air under pressure into said reduction chamber tangentially and centrifugally, and a plurality of crushing rollers pivotally suspended upon said drive head and adapted to act in conjunction with the attrition ring to reduce the raw material, together with a plurality of plows suspended upon said drive head, and alternating in position with the crushing rollers, for the purpose set forth.
  45. 9. In pulverizing apparatus of the character designated, in combination, a reduction chamber, means for feeding raw material thereto, a fixed attrition ring positioned in said reduction chamber, means positioned centrally with relation to said attrition ring for projecting air under pressure into said reduction chamber tangentially and centrifugally, and a plurality of crushing rollers pivotally suspended upon said drive head and adapted to act in conjunction with the attrition ring to reduce the raw material, together with a plurality of plows suspended upon said drive head, and alternating in position with the crushing rollers, for the purpose set forth.
  50. 10. In pulverizing apparatus of the character designated, in combination, a reduction chamber, a fixed attrition ring positioned therein, crushing rollers rotatably mounted to act in conjunction therewith, means for feeding raw material to said reduction chamber, plows for agitating the raw material and feeding same to the crushing rollers, and means positioned centrally with relation to said attrition ring for projecting air under pressure into said reduction chamber centrifugally and tangentially, for the purpose described.
  55. 11. In pulverizing apparatus of the character designated, in combination, a reduction chamber, a fixed attrition ring positioned therein, crushing rollers rotatably mounted to act in conjunction therewith, means for feeding raw material to said reduction chamber, plows for agitating the raw material and feeding same to the crushing rollers, and means positioned centrally with relation to said attrition ring for projecting air under pressure into said reduction chamber centrifugally and tangentially, for the purpose described.
  60. 12. In pulverizing apparatus of the character designated, in combination, a reduction chamber, a fixed attrition ring positioned therein, crushing rollers rotatably mounted to act in conjunction therewith, means for feeding raw material to said reduction chamber, plows for agitating the raw material and feeding same to the crushing rollers, and means positioned centrally with relation to said attrition ring for projecting air under pressure into said reduction chamber centrifugally and tangentially, for the purpose described.
  65. 13. In pulverizing apparatus of the character designated, in combination, a reduction chamber, a fixed attrition ring positioned therein, crushing rollers rotatably mounted to act in conjunction therewith, means for feeding raw material to said reduction chamber, plows for agitating the raw material and feeding same to the crushing rollers, and means positioned centrally with relation to said attrition ring for projecting air under pressure into said reduction chamber centrifugally and tangentially, for the purpose described.

- reduction chamber tangentially and centrifugally, a central bearing sleeve extending therethrough, a drive shaft and drive head mounted in and on said central bearing sleeve, a plurality of crushing rollers pivotally suspended upon said drive head and adapted to act in conjunction with the attrition ring to reduce the raw material, a plurality of plows suspended upon said 5 drive head and alternating in position with said crushing rollers, and means for effecting the vertical adjustment of said plows with relation to the attrition ring and crushing rollers, for the purpose described.
- 10 15 10. In pulverizing apparatus of the character designated, in combination, a reduction chamber, means for feeding raw material thereto, a fixed attrition ring positioned in said reduction chamber, means positioned centrally with relation to said attrition ring for projecting air under pressure into said reduction chamber tangentially and centrifugally, a central bearing sleeve extending therethrough, a drive shaft and drive head 20 25 mounted in and on said central bearing sleeve, a plurality of crushing rollers pivotally suspended upon said drive head and adapted to act in conjunction with the attrition ring to reduce the raw material, a plurality 30 35 of plows suspended upon said drive head and alternating in position with said crushing rollers, and means for effecting the lateral adjustment of said plows with relation to the attrition ring and crushing rollers, for the purpose described.
11. In pulverizing apparatus of the character designated, in combination, a reduction chamber, means for feeding raw material thereto, a fixed attrition ring positioned 40 45 50 55 in said reduction chamber, means positioned centrally with relation to said attrition ring for projecting air under pressure into said reduction chamber tangentially and centrifugally, a central bearing sleeve extending therethrough, a drive shaft and drive head mounted in and on said central bearing sleeve, a plurality of crushing rollers pivotally suspended upon said drive head and adapted to act in conjunction with the attrition ring to reduce the raw material, a plurality of plows suspended upon said drive head and alternating in position with said crushing rollers, and means for effecting both the vertical and lateral adjustment 60 65 70 75 80 85 90 95 100 105 110 115 120 125 130 of said plows with relation to the attrition ring and crushing rollers, for the purpose described.
12. In pulverizing apparatus of the character designated, in combination, a reduction chamber, a fixed attrition ring positioned therein, means for feeding raw material to said reduction chamber, a central bearing sleeve extending therethrough, a drive shaft and drive head mounted in and on said central bearing sleeve, a plurality 60 65 70 75 80 85 90 95 100 105 110 115 120 125 130 of crushing rollers pivotally suspended upon said drive head and adapted to act in conjunction with the attrition ring to reduce the raw material, a plurality of plows suspended upon said drive head and alternating in position with said crushing rollers, means for projecting air under pressure into said reduction chamber centrifugally and tangentially toward the direction of travel of said plows and crushing rollers but opposed to the direction of rotation of said crushing rollers, and means of withdrawing air from said reduction chamber, for the purpose described.
13. In pulverizing apparatus of the character designated, in combination, a reduction chamber, a fixed attrition ring positioned therein, means for feeding raw material to said reduction chamber, a central bearing sleeve extending therethrough, a drive shaft and drive head mounted in and on said central bearing sleeve, a plurality of crushing rollers pivotally suspended on said drive head and adapted to act in conjunction with said attrition mill to reduce the raw material, a plurality of plows suspended upon said drive head and alternating in position with said crushing rollers, an air pressure compartment underneath said reduction chamber formed with a central opening thereinto, and means positioned centrally with relation to said attrition ring for projecting the air from said pressure compartment centrifugally and tangentially, for the purpose described.
14. In pulverizing apparatus of the character designated, in combination, a reduction chamber, a fixed attrition ring positioned therein, means for feeding raw material to said reduction chamber, a central bearing sleeve extending therethrough, a drive shaft and drive head mounted in and on said central bearing sleeve, a plurality of crushing rollers pivotally suspended on said drive head and adapted to act in conjunction with said attrition mill to reduce the raw material, a plurality of plows suspended upon said drive head and alternating in position with said crushing rollers, an air pressure compartment underneath said reduction chamber formed with a central opening thereinto, and tangential deflectors arranged in conjunction with said central opening, whereby the air from said compression compartment is projected tangentially and centrifugally into the reduction chamber, for the purpose described.
15. Pulverizing apparatus of the character designated, comprising a reduction chamber, a fixed attrition ring positioned therein, means for feeding raw material to said reduction chamber, a central bearing sleeve extending through said reduction chamber, a drive shaft and drive head mounted in and on said central bearing

sleeve, a non-rotatable spindle suspended on a rocker bearing having a trunnion shaft journaled on said drive head, and a crushing roller rotatably mounted on said 5 non-rotatable spindle, and adapted to act in conjunction with said attrition ring, for the purpose described.

16. Pulverizing apparatus of the character designated, comprising a reduction 10 chamber, a fixed attrition ring positioned therein, means for feeding raw material to said reduction chamber, a central bearing sleeve extending through said reduction chamber, a drive shaft and drive head 15 mounted in and on said central bearing sleeve, a non-rotatable spindle suspended on a rocker bearing having a trunnion shaft journaled on said drive head, and a crushing roller rotatably mounted on said non- 20 rotatable spindle, and adapted to act in conjunction with said attrition ring, said crushing roller consisting of a tire section screwing onto a threaded hub section of a rotatable sleeve mounted on an annular 25 shoulder on said non-rotatable spindle, for the purpose described.

17. Pulverizing apparatus of the character designated, comprising a reduction chamber, a fixed attrition ring positioned 30 therein, means for feeding raw material to said reduction chamber, a central bearing sleeve extending through said reduction chamber, a drive shaft and drive head mounted in and on said central bearing 35 sleeve, a non-rotatable spindle suspended on a rocker bearing having a trunnion shaft journaled on said drive head, and a crushing roller rotatably mounted on said non-rotatable spindle, and adapted to act in

conjunction with said attrition ring, said 40 crushing roller consisting of a tire section screwing onto a threaded hub section of a rotatable sleeve mounted on an annular shoulder on said non-rotatable spindle, the thread connection between the hub section 45 of said rotatable sleeve and the tire section of the crushing roller being reversed in pitch as related to the direction of rotation of the said crushing roller, for the purpose described.

18. Pulverizing apparatus of the character designated, comprising a reduction chamber, a fixed attrition ring positioned therein, means for feeding raw material to said reduction chamber, a central bearing sleeve extending through said reduction chamber, a drive shaft and drive head mounted in and on said central bearing sleeve, a non-rotatable spindle suspended on a rocker bearing having a trunnion 60 shaft journaled on said drive head, and a crushing roller rotatably mounted on said non-rotatable spindle, and adapted to act in conjunction with said attrition ring, said crushing roller consisting of a tire section 65 screwing onto a threaded conoidal hub section of a rotatable sleeve mounted on an annular shoulder on said non-rotatable spindle, the thread connection between the hub section of said rotatable sleeve and the tire 70 section of the crushing roller being reversed in pitch as related to the direction of rotation of the said crushing roller, for the purpose described.
